(57) **CLAIM**

The ornamental design for an electronic device charger, as shown and described.

DESCRIPTION

FIG. 1 is a perspective view of an electronic device charger.

FIG. 2 is a rear view of the electronic device charger.

FIG. 3 is a left side view of the electronic device charger.

FIG. 4 is a top view of the electronic device charger.

FIG. 5 is a right side view of the electronic device charger; and,

FIG. 6 is a front view of the electronic device charger. The broken lines in the drawings depict portions of the electronic device charger that form no part of the claimed design.
